UNITED STATES PATENT OFFICE

JOHN EARL BOWKER, OF IVANHOE, NEAR MELBOURNE, VICTORIA, AUSTRALIA

DEVELOPING UNIT FOR X-RAY AND OTHER PHOTOGRAPHIC FILMS

Application filed April 30, 1930, Serial No. 448,687, and in Australia June 26, 1929.

This invention relates to a self-contained developing unit for X-ray and other photographic films and has been devised not only to reduce the cost of developing and the time occupied therein, but also to eliminate the expensive and unhygienic dark rooms and the accessories therefor at present employed for this purpose.

The invention is directed to a self contained unitary or composite cabinet for the development of X-ray and other photographic films in an expeditious manner, the cabinet being usable in a room open to light thus eliminating the necessity for a dark room, while the compactness of the cabinet enables it to be readily transported, and further advantages and features thereof will be apparent from the foregoing description.

The invention has for its object the provision of a self contained cabinet of the hand-insertion type having embodied therein a dark chamber and means combined therewith whereby the operator standing in a room open to light may carry out all the steps necessary in film development within the cabinet, including the unloading of the film from a cassette, immersion of the film in a developing tank, rinsing tank, fixing tank and washing tank, and then effect the passing of the developed film into a drying chamber.

A further object of the invention is to provide a self contained cabinet with light-tight means to permit the insertion of the operator's hands into a dark chamber embodied in the cabinet which also incorporates a cassette, film, and hanger magazines and developing, fixing, washing and rinsing tanks and means whereby the film can be transferred to any one of the members and thence to a drying chamber, all the members described being disposed within the cabinet which is provided with inspection panels or windows and means for diffusing the interior of the dark chamber with varying colored lights, as will be hereinafter described.

In order that the invention may be more readily understood it will now be described with reference to the accompanying drawings in which:—

Figure 1 is a view in front elevation of one form of the developing unit, and

Figure 2 is a plan thereof.

Figure 3 is a view in front elevation of the developing unit illustrating the interior of the cabinet.

Figure 4 is a sectional plan taken on line A—A, Figure 1.

Figure 5 is a vertical central section of the developing unit.

Figure 6 is a fragmentary plan view in detail of the hanger magazine.

Figure 7 is a plan view of one of the tanks employed in the developing unit, and

Figure 8 is a section taken on line B—B of Figure 7.

Figure 9 is a transverse sectional view of the tank illustrated in Figures 7 and 8.

Figure 10 is a view in transverse section of a film tray, and

Figure 11 is a fragmentary plan thereof.

Figure 12 is a sectional view of the drying chamber of the developing unit illustrating the movement of the film tray.

Figure 13 is a perspective view of a film hanger employed in this invention, and

Figure 14 is a fragmentary view in elevation of the adjustable arm on the hanger.

Figure 15 is a fragmentary perspective view of a modified form of film hanger.

Figure 16 is a side sectional view illustrating the shape of the leaves of the cassette magazine.

Figures 17 and 18 are views of the wiring diagrams of the heating and drying system and the lighting system respectively of the developing unit.

Figure 19 is a fragmentary sectional view embodying automatic means for emptying and filling the tanks employed in the unit.

Figure 20 is a sectional view of an alternative upper door usable in the developing unit.

Figure 21 is a section taken on line C—C, Figure 20.

Figure 22 is a view in plan of a magazine for use in dental or small photographic film work, and

Figure 23 is a section taken on line D—D, Figure 22.

Figure 24 is a front elevation of a develop-

ing unit embodying the principle of the larger unit but usable where the volume of work does not warrant the installation of the larger unit.

5 Figure 25 is a vertical section of the unit illustrated in Figure 24.

Figure 26 is a perspective view illustrating the interior of a developing unit for use in handling smaller photographs.

10 Figure 27 is a view in elevation of a hanger employed in developing small photographs.

15 The invention is directed to a product or unit which is self-contained and which is directed to a cabinet to replace the dark rooms now employed for the development of X-ray and other photographic films.

20 According to the apparatus illustrated in Figures 1 to 19, a cabinet 5 of suitable material is divided into upper and lower compartments 6, 7 from the horizontal centre 8.

25 The lower compartment 7 is divided into a plurality of smaller compartments 9, 10, 11, 12, 13, while the upper compartment 6 is adapted to be opened to all the said smaller compartments 9 to 13.

30 The upper compartment 6 at one end is provided with a drying compartment 14 normally closed from said compartment 6 by a hinged door 15 and this compartment 14 is open to the lower drying compartment 13 in line therewith at that end of the cabinet.

35 The upper compartment 6 forms the working chamber of the unit and in work is light tight, while at the back of this chamber 6 is a window 16 behind which a white light 17 and also (if desired) a red light is disposed, the glass of the window being frosted or is formed of flashed opal or other suitable dif-

40 fusion material so that while in work the completed films can be inspected in the manner required in pathological surveys if so desired.

45 A red or ruby glass inspection window 18 or windows is or are positioned at an inclination at the front top position or in any other suitable position of the cabinet 5 and a red or ruby lamp or lamps 19 is or are provided with the rear of the cabinet 5 to throw 50 the light into the enclosed compartment 6 in the required position, so that in this compartment the correct light tone necessary for developing is achieved in the compartment 6, as this light is required for inspection and work in the chamber and the ruby or red light does not throw any shadow during the working operations.

55 The compartment 6 during the developing period is closed by a light tight door or preferably two doors 20, 21, adapted to open outwardly and close inwardly to the centre 22.

These doors 20, 21 are provided with openings 23 around which are mounted sleeve covers 24 of fabric or other flexible opaque

material, the material used being preferably elastic or stretchable so that the hands of the operator are free to work within the cabinet 5 to effect all the steps of developing the films, thus providing light covers for the arms of the operator, and when not in use these sleeve covers may be covered by hinged flaps (not shown) to maintain the cabinet appearance of the unit.

70 The compartment 9 is divided at 25 to provide a storage chamber 26 and a cassette magazine chamber 27, the magazine chambers being formed by partitions and are graduated as at 26a to accommodate varying sizes of cassettes and so that they are all in alignment at the top.

75 The cassette magazine 27 is open at the top but is normally closed from the compartment 6 by a sliding cover 28, preferably lead lined, which is adapted to be moved over the top 29 of the compartment 26 so that the cassettes can be removed as required from the magazine 27 by the hands of the operator working within the compartment 6.

80 These magazine chambers 27 are preferably open at the front 27a to facilitate the placing of the cassettes in the magazine, which is more conveniently effected by the opening of the door 30 at the front 27a and passing the cassettes into the magazine from 85 the front to the rear.

85 Below the magazine chambers 27 is a space 90 in which is placed a slidable tray 31 which receives waste matter such as the paper or other covers of the used films, a space 32 being provided at the back of the magazine 27 by stepping as illustrated to allow the waste matter to drop through from the compartment 6 into the tray 31.

95 After the removal of the required films 105 from the cassettes the slide 28 is returned to cover the magazine 27.

100 The compartment 10 receives a sliding film hanger magazine in the form of a drawer 33 which is provided with a plurality of chambers 34 formed by the partitions 35 in which the supply of hangers is positioned, the hangers being suspended therein by projections formed thereon as hereinafter described which rest in grooves 36 formed in the top 110 of the chambers 34.

115 In the compartment 11 a film box magazine 37 is disposed, the magazine compartments 38 of which are shaped to receive boxes of 120 films of varying sizes but with the top of the boxes flush with the top of the compartments 38.

125 These compartments 10 and 11 are normally closed by a door 39 positioned in the front of the cabinet.

130 Covering the compartments 10 and 11 is a working tray or bench 40 which is adapted to slide so that it covers or uncovers the magazines 33 and 37, it being obvious that when the operator is at work in the compartment 6,

the bench 40 covers these magazines 33 and 37.

At the rear of the compartment 6 above these magazines 33 and 37 is a V or other shaped pocket 41 to receive the cassettes or 5 hangers during any of the operations required in developing the films.

The compartment 12 has mounted or depending therein a plurality of tanks which may be of any number as required according 10 to the work, but as illustrated, four tanks are shown, comprising a developing tank 42, a rinsing tank 43, fixing tank 44 and washing tank 45.

These tanks are provided with rims 42a 15 around the top thereof which seat on a transverse member 42b in the compartment 12 having openings 42c therein through which the tanks depend, to provide for the suspension thereof.

20 A cover 46 is provided for the tanks 42, 43 and 44, and this cover functions to automatically drain into the washing tank 45 which is uncovered by means of a corresponding opening 46a in the cover 46 which is preferably 25 set at a slight incline as at 46b towards the tank 45.

The cover 46 normally fits over the tanks so as to exclude the light from the developing and fixing tanks 42 and 44 respectively and 20 also to allow the water draining off the films being viewed to run back into the washing tank 45 thereby maintaining the solutions in the developing and fixing tanks free from contamination and at a constant strength.

25 By maintaining the washing tank 45 uncovered as illustrated, films may be readily removed therefrom for inspection purposes.

The cover 46 is hinged at 47 so that it can be swung out of the way as desired against 30 the door 15 of the drying chamber 14 as illustrated in Figure 5.

An auxiliary heating lamp or unit 48 is disposed in the chamber 12 to provide the required temperature therein, while the developing tank 42 has mounted thereon a heating unit or units 49 which form a part thereof adapted to maintain a temperature in the tank from 50° F. to 70° F. and to maintain a positive temperature of approximately 65° 35 F. for any length of time.

These electrical heating units on the tank 42 are mounted at any suitable point or points around or adjacent to the outer surface of the tank 42 containing the developer 45 but preferably at the bottom thereof as illustrated in Figure 3.

After the films have been developed the operator opens the door 15 and slides a support or supports 50 fitted with hooks 51 from 50 the upper drying chamber 14 into the compartment 6 so that he can suspend the hangers carrying the developed films on said hooks 51, and after hanging the films, the slide 50 is moved back into the drying chamber 14 65 and the door 15 closed to allow further de-

veloping in the compartment 6 and the films suspended in the drying compartment remain there during the drying period.

On the accumulation of films in the drying compartment 14 the door 52 is opened and the 70 dried or partly dried films are removed therefrom but if necessary the films are hung in the lower drying chamber 13 on a similar slide 53 fitted with suspension hooks and thus the films can be subjected to a further drying 75 operation.

The slide 53 can be moved outwardly after the opening of the door 55 of the lower drying compartment 13.

80 In the lower drying compartment 13 is a combined air fan and heating element 56 of any suitable type, which circulates the heated air through the chambers 13 and 14 to assist the drying of the films.

The developing, fixing and washing tanks 85 42, 44 and 45 respectively are provided with a thermo siphon system of circulation which consists in providing spaced baffles 57 at each end of the tanks with a clearance 58 between the walls, the baffles 57 terminating at 90 a point above the bottom of the tanks and are united at the top with spaced distance pieces 59, the distance pieces forming guides for hangers carrying the films and so that a maximum number of hangers may be placed 95 in the tanks without abrading the neighbouring films.

Should excess heat be imparted for any reason the chemical or liquid is prevented 100 from spilling over the top of the tanks by the thermo siphon action of the liquid which will circulate upwardly over the baffles 57 and down through the clearances 58 back into the tank 44 or 45.

This circulation of the solution also acts 105 as an automatic solution agitation whereby an even density of the solution is maintained.

The film hangers are preferably of special 110 construction and of non-corrosive material and are illustrated in Figures 13, 14 and 15.

These hangers are directed, firstly, to hold the films without the undue bulging that occurs in using the present type; secondly, in the rapid and effective manner in which the films are dropped or inserted therein and maintaining the said films in a substantially flat position in said hangers; and thirdly, in providing means whereby the smallest to the largest hanger can be suspended in the tanks. 115

In the construction of hanger as illustrated 120 in Figures 13 and 14, an upper plate 59 is provided and from the sides at the top lugs or ears 60 longitudinally extend, which when in position, rest on the flanges 61 of the developing tanks 42, 43, 44 and 45.

From this plate 59 a skeleton framework 62 of rectangular or other shape depends and the sides and bottom of this framework 62 are grooved as at 63 inwardly from the inner 125

edge so that in cross section they take the form of a U or V channel.

Thus a front and rear backing is provided for the edges of the film, but the front face 62a does not extend to the top of the upper plate 59 being cut out as at 64 some distance below, and has its upper edge 65 flanged or flared outwardly, so that the flaring and the upper top plate 59 form a support for the leading end of the film as it is slipped into the hanger into position in the channel at the sides and bottom of the hanger.

The bottom edge and the sides of the hanger are formed with a series of spaced holes 66 to allow of the drainage of the solution therefrom when the hanger is removed from the tanks.

As illustrated in Figure 15 the hanger is designed for dropping the films vertically therein and in this construction the front upper plate 62a is extended up to the level of the top of the back plate 59 and one or both of these plates is or are flared outwardly as at 67 to provide a simple lead in for the edge 25 of the film.

Combined with the hangers are means to allow the smallest hanger to be suspended in the tanks and magazines and these means preferably consist of an arm 68 pivoted at 69 to one of the lugs 60 and which arm 68 is adapted to swing to horizontal position to extend and rest on the opposite side of the tank or magazine and when not in use the arm 68 is adapted to swing down and remain in line 35 with one of the sides of the hanger.

The various magazines 27, 33 and 37 are cut away as at 70 at their top and sides to facilitate the removal of the articles stored therein.

As above described the red lamps 19 are disposed so that the rays thereof are spread into the upper developing chamber 6, while the rear right hand side at the back is provided with a sheet or pane of frosted 45 or flashed opal glass 16 or other material capable of diffusion behind which is disposed as at 17 red or white and red and white lights so as to allow of the rays lighting up the finishing end of the chamber for inspection of the film or for other purposes such as a pathological report.

The white lamp 17 and the red lamps 19 are arranged in circuit as illustrated in Figure 18 with switches 71, 72 in said circuit to control the lighting requirements, the switch 71 controlling the lamps 19 and the switch 72 controlling the lamp 17.

The heating lamp 48, the heating unit 49 of the developing tank 42 and the drying fan 60 56 are arranged in a common circuit as illustrated in Figure 17, the respective elements being controlled by separate switches respectively 73, 74 and 75.

In order to prevent damage by the undue 65 retention of the heat caused by the elements,

a pilot light or other indicator may be disposed in the circuit or if desired, the elements may be under thermostatic control.

Each of the tanks 42, 43, 44 and 45 is provided with a delivery outlet 76 and each is fitted with a non-corrosive flexible delivery pipe 77 fitted with valves or clips 78 to normally close the delivery ends thereof.

As illustrated in Figure 19 the tanks 42, 43, 44, 45 may be automatically filled from 75 or emptied into supply tanks 79 by means of non-corrosive pipes 83, the tanks 79 being arranged on a platform 80 vertically disposed in a frame or compartment of the cabinet 5, the platform 80 sliding on guides 81 against the pull of compensating weights 82 so that when the supply tanks 79 are below the level of their respective tanks 42, 43, 44, 45 the liquid in said latter tanks flows by gravity into the receiving tanks 79 but when the tanks 85 79 are in their raised position, as illustrated, the liquid in the said tanks 42, 43, 44, 45 is maintained at a constant level.

In the modification illustrated in Figures 90 20 and 21, the double doors 20-21 of the compartment 6 may be dispensed with and in lieu thereof a door 83 hinged along the bottom edge may be employed, the said door being fitted with a plurality of sleeve covers 95 24 along the length thereof while the lower rail 84 of the door may be cut away to receive a flap door 85 which when opened, as illustrated in Figure 21, allows the insertion of cassettes and/or hangers or other articles into the compartment 6.

The doors, slides, walls and any other portion of the cabinet 5 as required are lined with lead or non-corrosive material and in such a manner that all the parts relating to the compartment 6 are immune to light rays while the lead linings are non-penetrative thereby preventing stray X-ray or secondary rays from reaching or affecting the films in the magazine.

In the modification illustrated in Figures 105 24 and 25 a cabinet is shown to be employed where the volume of work is not sufficient to warrant the use of the larger cabinet and parts above described.

According to this construction the cabinet 115 is formed with the upper compartment 6 fitted with a hinged door 86 along the rail 87, the door being provided with sleeve covers 88, inspection window of red or ruby material, a red lamp holder 90, a glass pathological survey pane 16a with a white or red, or both white and red lamps 17a behind it.

It will be noticed that in this construction the drying chambers 13, 14 are dispensed with.

The lower portion of the cabinet 5a is divided into two separate compartments 91, 92, the one compartment 91 being lead lined and utilized for the storage of cassettes, hangers, 125 films and other articles required in the de- 130

velopment of the films and these articles are transferred to the upper compartment 6 by the operator prior to commencing the work.

Above this compartment 91 is the work bench 93 which is adapted to slide over the developing tanks as and when required.

The developing tanks in this instance are of suitable number, three being illustrated, comprising a developing tank 94, fixing tank 95 and washing tank 96, the developing tank 94 being provided with a heating element 97 mounted on the base or other portion thereof, the tanks being disposed in the compartment 92 and the compartments 91, 92 are covered by hinged doors 98.

In the construction of cabinet illustrated in Figures 22, 23 and 26, the apparatus is modified so as to be adapted for small film work such as is required by dentists and apprehends a self-contained cabinet 99, a film till or magazine 100 and a special construction of hanger.

This cabinet 99 follows the outline illustrated and comprises an upper compartment 101 extending along the entire width which is normally closed by the hinged doors 102 and a hinged frame provided with a ruby red inspection window 104, each door 102 having a sleeve cover 103 fitted therein.

The top of the cabinet is provided with ruby red inspection windows 104, 105 and a pathological inspection window 106 and lamps are arranged substantially as and for the purposes above described.

The inspection window 104 is formed in a casing 107 which is adapted to close over the space between the doors 102 to normally insure that the compartment 101 is immune from light rays.

This casing 107 is adapted to swing upwardly and rearwardly as illustrated on its hinges 108, or it may be adapted to slide upwardly and rearwardly to allow of the cabinet to be used as a desk and also to allow of an inspection of the developed films in the hanger 109 when it is disposed in the developing compartment.

At the bottom of the developing compartment 101 is a work bench 110 and to the side thereof is a hinged cover 111 normally covering the developing tanks, three in number being illustrated, comprising a developing tank 112, fixing tank 113 and washing tank 114, the said tanks being suspended in the lower compartment 115 which is normally closed at the front thereof by a door 116, the developing tanks being heated in the manner above described.

The hinged cover 111 during the developing of the films is adapted to be swung upwardly against the adjacent wall 117 of the cabinet and is held thereto by a suitable catch.

The lower compartment 118 fitted with a lead lined closure door 119 is adapted to

store the magazine for the finished films, a magazine or carrier for undeveloped films, hangers and other articles required for developing.

The central rail 120 of the cabinet is fitted with a pass drawer 121 positioned below the bench 102 which is hinged at the front edge so that it can be raised and the films to be developed removed from the pass drawer 121 and fitted into the hanger 109 within the developing compartment 101.

The bench 102 is then returned to allow of the necessary development stages.

I desire it to be understood that by a simple variation the left hand side of the dark chamber 6 can be provided with a series of spaced shelves or partitions adapted to receive the cassettes and hangers before, during or after the operations of film development in said dark chamber 6.

The hanger 109 employed in this work consists of a frame set with spaced tiers 122 of film receivers 123 arranged one below the other, some of which, as at 124, may be adapted to allow the films to be set with the short ends lengthwise and some as at 123 with the short ends sidewise in the hanger according to the method of photography.

On the face of the cross members of the frame is a plurality of narrow spaced vertical flanges or lugs 125 turned inwardly and between these spaced vertical flanges at the bottom is a further flange or lug 126 bent outwardly and upwardly, the space between the wall 127 of the hanger and the flanges 125, 126 being sufficient to allow of the easy sliding therein of the edges of the film, a plurality of which can thus be supported in a single hanger.

It will be obvious that the means for suspending the films in the hanger may be varied if so desired.

The hanger frame 109 thus provides for the mounting of multiple film carriers and the carriers may receive the films in the sequence of exposure of the films as above described.

The hanger frame 109 may also be provided at the top with the side suspension lugs 60 and pivoted extension arm 68 as above described.

The preferred form of till or magazine for small films such as required for dentists' use is illustrated in Figures 22 and 23 and consists of a rectangular box 127 with a row of compartments 128 on either side of the longitudinal centre, each compartment being of a size to comfortably receive an exposed film which is received therein at an inclination owing to each wall 129 of the compartments being set at an angle to the side edges of the box.

This box 127 forms a magazine for the films and at one or both ends of the magazine is a compartment 130 which is adapted to re-

ceive a stock of uncovered films, the wrappers of which are marked with an indicator to allow of the use in sequence as above described, while the compartments 128 are also marked in sequence to follow the proper form of placing as the exposed films are arranged therein.

Each row of compartments 128 in the magazine 127 is fitted with a lid 127a hinging along the centre and closing over its respective compartment.

Prior to commencing operations the solutions for the developing and fixing tanks 42 and 44 respectively are prepared and the tanks filled and also the rinsing and washing tanks 43 and 45 are filled with water and the cover 46 closed over the tanks as illustrated.

The arms of the operator are inserted in the extensible sleeve covers 24 through the orifices or openings thereof.

In the operation embodied in the invention the steps are effected in the following cycle:—

The cassette carrying the exposed film is transferred from the magazine 27 to the chamber 6 after sliding the cover 28 to one side.

The light is prevented after this step from entering the inside of the cabinet compartment 6 by the slide 28 which is returned to cover the magazine 27 and the ruby red lights 19 are switched on so that the interior of the said compartment is diffused with a corresponding color essential for the process of developing the films.

The slide 28 having been returned back to the normal position over the magazine 27, the cassette is then placed on the slide 28 which forms the working bench.

The cassette is then opened and the exposed film removed.

The operator withdraws his arms from the sleeves 24 and switches on the heating element 45 of the developing tank 42 till the solution therein reaches the correct temperature.

The slide 28 is then pushed to the left hand side to allow of access to the hanger magazine 59 and the film is then dropped or placed in a hanger 59 of suitable size which is removed by the other hand of the operator from the magazine 33.

The hanger 59 with the exposed film is then removed from the slide 28 and placed in the developing tank 42 which is uncovered together with the adjacent tanks 43 and 44 by raising the cover 46 to the vertical position against the door 15.

After the exposed film in the hanger 59 has been inserted in the developing tank 42 by the right hand of the operator, the slide 28 is returned to normal position over the magazines 27, 33 with the left hand.

The cassette is then returned to the magazine 27 or chamber 26 to be used for a fur-

ther exposure of films when required.

After 5 minutes, indication is given by a time bell or other timing mechanism or signal, preferably a clock 131, that the film is developed and the hands are then placed inside the extensible sleeves and the slide 28 is then pushed to the left.

The film is taken from the developer 42 rinsed in the water tank 43 and placed in the fixing tank 44.

After 10 minutes or thereabouts, the film is taken from the fixing tank 44 and placed in the washing tank 45.

This last operation can be effected in daylight with the door or doors of the dark chamber 6 open.

After suitable washing, the film with the hanger can then be placed in a special container or be arranged in front of the view light 17 and over a gutter to allow drainage back to the washing tank 45 and the cover 46 is returned over the tanks 42, 43, 44, 45.

The white light 17 at the rear of the pathological survey window 16 is then switched on whereby the film can then be viewed and reported on pathologically or otherwise.

After this step, the inner door 15 of the drying chamber 14 is opened to allow the slide 50 on which the hanger is supported to be moved into the drying chamber 14 and this operation, if necessary, can be effected in the dark.

The drying fan 56 is then switched on to facilitate the drying of the film.

After drying the film is taken from the drying chamber 14 without the admission of light, into the inside dark chamber 6 or the films may be removed for storage or inspection.

After the drying of the film or films has been completed all switches are turned off.

Behind the sleeve covers 24 a covering flap is adapted to drop when the arms are removed to ensure a light-tight mounting while, in some instances, the apparatus may be made up with or without several of the features such as the pass drawer, the magazine, white light, the drying chamber and emptying and filling appliance and still be able to operate for developing purposes as above described.

I desire it to be understood that the parts liable to be effected by the solutions are preferably formed of non-corrosive material and other parts or chambers suitably lined, such as with lead to protect them from the stray or secondary rays.

The apparatus and method embodying the essential features and functions and for the purposes above described will be of great utility and embodies parts which in their ordinary and separate use, will be of great value in developing films and a distinct advance in the art, and I desire it to be understood that modifications, improvements and

variations may well be evolved within the ambit of the invention as herein described without departing from its spirit and scope.

What I claim as my invention and desire to secure by Letters Patent is:—

5. 1. Means for developing X-ray and other photographic films, comprising a unitary cabinet of the hand insertion type in which all the operations required in a dark room 10 may be effected, a dark chamber within said cabinet having in combination therewith cassette and hanger magazines, developing, rinsing, fixing and washing tanks and a drying chamber, and light-tight sleeve covers for 15 the reception of the operator's arms to permit a film to be transferred to and from any one of the units within the cabinet.

2. In means for developing X-ray and other photographic films, a unitary cabinet, 20 light-tight and flexible sleeve covers disposed at the front thereof, to permit the insertion of the operator's arms within the cabinet, a dark chamber within said cabinet, and a series of lead-lined compartments positioned 25 below the dark chamber in which are disposed respectively cassette, film and hanger magazines, developing, rinsing, fixing and washing tanks, and a drying chamber.

3. In means for developing X-ray and other photographic films, a unitary cabinet of the hand insertion type, comprising in combination a casing, the upper portion of which is formed as a dark chamber, the lower portion of said casing being divided into a 30 series of lead-lined compartments to provide space for a storage chamber, cassette, film and hanger magazines and developing, rinsing, fixing and washing tanks respectively, a drying chamber communicating with the dark chamber but normally closed therefrom, a lead-lined slide in the bottom of the said dark chamber disposed over the magazine compartments and usable as a working bench, light-tight and flexible sleeve covers for the 35 reception of the operator's arms whereby the films may be transferred to and from the various units within the cabinet, means for diffusing varying colored lights into the dark chamber, and an inspection panel of ruby 40 glass at the front of the cabinet near the top thereof.

4. In means for developing X-ray and other photographic films, a unitary cabinet of the hand-insertion type, a dark chamber 55 in the upper portion of said cabinet, the lower portion of which is divided to provide storage space and a further space for suspending a developing tank, a fixing tank, a rinsing tank, and a washing tank, means attached to 60 the developing tank for supplying heat thereto, means to provide access to the said tanks from inside the dark chamber, a red or ruby colored inspection panel directed into said chamber, doors at the front of said dark 65 chamber, light-tight and flexible sleeve covers

fitted in the said doors for the reception of the arms of the operator, means for diffusing the interior of the dark chamber with a ruby colored light, an inspection window within the said dark chamber with exterior means for diffusing a white light therethrough for the purposes herein specified. 70

5. In means for developing X-ray and other photographic films, a cabinet of the hand-insertion type, comprising a casing embodying in combination a compartment above a central table adapted to form a dark chamber, a work bench slidably mounted on said table in the dark chamber, doors to close the dark chamber while in operation in conjunction with a movable central portion hingedly mounted on the cabinet, light-tight and flexible sleeve covers in the dark chamber doors, a storage chamber below the central table, an adjacent chamber below the said table in which is suspended developing, fixing and washing tanks, means on said developing tank for supplying heat thereto, a hinged cover normally closing the said tanks from the dark chamber, a drawer in the casing adapted to pass articles or material into the said dark chamber, an inspection panel of ruby red in the central movable portion adapted to be directed into the dark chamber, an additional inspection window at the back of the said chamber, and means for diffusing, as desired, a red light or white light into the dark chamber. 80

6. In means for developing X-ray and other photographic films, a unitary cabinet 105 wherein a dark chamber has incorporated therewith cassette film and hanger magazines, and a series of developing tanks, the magazines being divided into a plurality of compartments of varying sizes to receive cassettes and hangers of corresponding sizes, means to prevent lateral movement of the hangers carrying films when in the developing tanks, comprising guideways disposed therein, and means for heating the main developing tank and automatically agitating the solution therein. 110

7. In means for developing X-ray and other photographic films, a cabinet having 115 in combination a dark chamber, magazines for cassettes, films and hangers, a developing tank, fixing tank, and washing tanks, the compartments of the magazines being cut away at the top and sides thereof to facilitate the removal of the contents, and spacing members disposed in the developing tanks to prevent lateral displacement of the hangers and contact between the films held thereby when suspended in the tanks. 120

8. In means for developing X-ray and other photographic films, a cabinet containing a dark chamber the doors of which are fitted with light-tight and flexible sleeves, covers, storage spaces below the said dark 125 room in which are disposed cassette, film and

hanger magazines, and a series of developing tanks, a drying chamber in combination with the dark chamber and developing tanks, means for slidably supporting the film carrying hangers in the drying chamber for passing the films from the said dark chamber into the drying chamber, door closure means between the dark chamber and drying chamber, and means for circulating heated air through the drying chamber as herein described.

9. In means for developing X-ray and other photographic films, a unitary cabinet of the hand-insertion type, in combination therewith a film magazine formed with a plurality of compartments arranged in rows, compartments at each end of the magazine adapted to receive uncovered films arranged in sequence, intermediate compartments in said cabinet, having inclined bases, each compartment being indicated whereby each film is arranged, and developed in sequence in the dark chamber of the cabinet.

Signed at Melbourne, Victoria, Australia,
25 this 31st day of March A. D. 1930.

JOHN EARL BOWKER.
